(57) **CLAIM**

The ornamental design for a drawer and frame system, as shown and described.

DESCRIPTION

FIG. 1 is a front view of a drawer and frame system showing my new design;

FIG. 2 is a front view of a frame for use in the system of FIG. 1, shown separately for completeness of illustration;

FIG. 3 is a rear view of FIG. 2;

FIG. 4 is a side view of FIG. 1, the opposite side view being identical thereto;

FIG. 5 is a top view of FIG. 1;

FIG. 6 is a bottom view of FIG. 1;

FIG. 7 is a front view of a drawer for use in the system of FIG. 1, shown separately for completeness of illustration;

FIG. 8 is a rear view of FIG. 7;

FIG. 9 is a side view of FIG. 7, the opposite side view being identical thereto;

FIG. 10 is a top view of FIG. 7; and,

FIG. 11 is a bottom view of FIG. 7.

The jagged broken lines surrounding the generally circular openings in the front views of the system and drawers indicate that no particular handle shape is being claimed, represent boundaries of the claimed design and form no part of the claimed design.

The remaining broken lines are for environmental purposes and form no part of the claimed design. Some of the features that may be visible through the transparent or translucent material on the frame or drawer have been removed for clarity.

The drawer and frame include a material shaded to indicate a transparent or translucent material.
